VACUUM SWITCH

Robert L. Norton, Santa Barbara, Calif., assignor to Penta Laboratories, Inc., Santa Barbara, Calif., a corporation of California

Application August 1, 1955, Serial No. 37,249

Term of patent 14 years

(Cl. D26—13)

The figure is a perspective view of the vacuum switch, showing my new design.

The opposite side of the vacuum switch is substantially identical with that shown.

Among the features of my design which characterize it as a vacuum switch resides in the shape and dimensions of the sinuous members bridging the spring which joins the switch armature to the horizontal output lead, all as illustrated.

I claim:

The ornamental design for a vacuum switch, substantially as shown and described.
